UNITED STATES PATENT OFFICE.

J CORBLEY POOL, OF SANTA BARBARA, CALIFORNIA.

OIL SEPARATOR.

1,418,970.

Specification of Letters Patent. Patented June 6, 1922.

Application filed February 18, 1920. Serial No. 359,506.

To all whom it may concern:

Be it known that J, J CORBLEY Pool, a citizen of the United States, residing at Santa Barbara, in the county of Santa Barbara and State of California, have invented certain new and useful Improvements in an Oil Separator, of which the following is a specification.

This invention relates to improvements in apparatus for separating hydrocarbon oils from rock through the process of distillation.

Prior to the conception of the present invention much oil has been lost through the lack of proper apparatus for cheaply and quickly separating the same therefrom. In some sections of the country considerable hydrocarbon oil is contained in rock of the shale variety and also in other types of rock and heavy sand. Heretofore it has been found that although the possible yield of such oil might be considerable the available apparatus has either been too expensive to operate or the process too slow in accomplishing the desired results. The present invention is designed to overcome these deficiencies in prior apparatuses by subjecting the oil bearing rock to sufficient heat to render the oil volatile and then trapping the volatile oil or vapor and condensing the same. Furthermore the invention contemplates utilizing heat usually lost both from the furnace and the cooling rock which has been relieved of its oil to pre-heat the oil bearing rock before it enters into the area heated by the furnace, thus materially decreasing the cost of obtaining the oil and expediting the operation of the process.

Still further objects of the invention are; the provision of means to facilitate delivering and carrying away the rock before and after treatment; to effect the creation of suction or a partial vacuum for expediting the carrying off of vapor or volatile oil; and to improve upon the heating apparatus by utilizing either gas or oil mixed with air for distilling the oils from the rock.

For the purpose of illustrating this invention, there is shown in the accompanying drawings one form thereof which is at present preferred, since the same has been found in practice to give satisfactory and reliable results, although it is to be understood that the various instrumentalities of which the invention consists can be variously

arranged and organized and that the invention is not limited to the precise arrangement and organization of these instrumentalities as herein shown and described.

In the drawings:

Figure 1 is a sectional side elevation of the apparatus.

Figure 2 is a vertical section on line 2—2 of Figure 1.

Figure 3 is a sectional view on line 3—3 of Figure 1.

Figure 4 is a sectional view on line 4—4 of Figure 1.

Like characters of reference indicate like or similar parts throughout the several views of the drawings, in which:

The frame or housing is designed to carry a plurality of separate and distinct distilling apparatuses as illustrated in Figures 2, 3 and 4, and comprises outer walls 1 and spaced inner walls 2 forming a central compartment A. The space between the inner walls 2 and outer walls 1 is divided into substantially cylindrical chambers B by partitioning walls 3 and the central compartment is roofed over as at 4 and provided with a central flat portion 5 upon which tracks are laid to receive stone cars, one of which is illustrated and designated C. The chambers B are also roofed over as at 6, and the said roof portion is provided with a central substantially V-shaped depression constituting a bin for storing rock dumped from the cars C. As shown in Figure 1, the V-shaped depressions are each provided with openings communicating with each of the several cylindrical chambers B for receiving the ends of tubes D one of which is contained in each of the chambers B and extends substantially the entire length thereof for receiving stone.

The tubes constitute stills, but the details thereof will be referred to as the description proceeds. At the base of the frame and between each of the partitions 3 and extending within the chambers B to a point adjacent the walls 2 are centrally depressed block members 7 upon each of which is supported endless belts 8 carried by rollers 9 and extending beneath the lower terminals of the tubes D. The walls 1 are cut away as at 10 to gain access to the endless belts, as illustrated, and also to communicate with the interior of the compartments.

At a point midway the top and bottom of

the outer walls 1 they are enlarged as at 11 and have formed therein passages 12 communicating with the upper and lower portions of each of the chambers B and constituting flues or by-passes, the purpose of which will hereinafter appear. Furthermore a plurality of chimneys 13 are provided, each of which communicate with the upper portion of one of the chambers B.

10 As heretofore set forth the tubes D extend from the V-shaped depressions in the roof 6 of the chambers to a point adjacent the endless belts 8, and they are of less diameter than the diameter of the chambers B and 15 are supported intermediate their extremities by pairs of transverse partitions 14, each pair of which extends from the walls 1 there-to from points below the upper terminations of the passages 12 and above their lower 20 terminations thus dividing the chambers B into upper, intermediate and lower compartments X, Y and Z respectively; the lowermost compartments Z, of which communicate with the uppermost compartments 25 X through the passages or flues 12.

Arranged between the lower partitions 14 are fuel burners 15 comprising gas and air inlet pipes 16 and 17 respectively delivering a mixture of the two to burners 18 extending 30 through the upper of the pair of partitions 14 and arranged in a circle (see Figure 4) to direct their flames against the portion of the tubes contained in the compartments Y which will hereinafter be termed the heating 35 chambers.

Arranged in the tubes D between both the upper and lower partitions 14 are valves 19 which when open lie flush with the walls of the tubes and are operated by suitable levers 40 or mechanism (not shown). The purpose of these valves is to divide the tubes D into upper, intermediate, and lower portions designated X^a, Y^a and Z^a for receiving rock during its different stages of treatment. 45 Specifically the rock is originally received in the portions X^a of the tubes where it is warmed, it is then delivered to portions Y^a by opening upper valves 19 where it is heated and the oils distilled or vaporized, where- 50 upon the lower valves 19 are opened and it passes to the portions Z^a where it is cooled preparatory to removing it by operation of the endless chains 8. Attention is here called to the fact that the heat generated 55 by the cooling rock or residue in portions Z^a passes from compartments Z of the chambers to the compartments X where it serves to pre-heat the portions X^a of the tubes containing the newly received rock awaiting 60 treatment, it being understood, of course, that the passage of rock down the tubes from portion to portion is a continuous operation.

In order to permit heat to pass from the compartment Y to the compartments X of the chambers, openings 20 are provided

which communicate with the flues 12 so that all surplus heat from both compartments Y and Z passes to compartments X for pre-heating the rock.

Arranged in the central compartment A are a plurality of conduits 21, each pair of which extend to a point adjacent the base thereof where they are connected with service pipes 22, beneath and communicating with which are suction fans 23 for creating a partial vacuum in the conduits 21. Branching from the conduits 21 are a plurality of equally spaced apart downwardly inclined pipes 24 communicating with the portions Y^a of the tubes for drawing off the vapors arising from the oil bearing rock as it is acted upon by the heat. Furthermore, another set of branch pipes 25 communicate with the portions Z^a as the rocks emanate vapors even while they are cooling. Consequently it will be seen that as the rock is subjected to the heat generated in compartments Y, the hydrocarbons will become volatile or will vaporize and be drawn off through the pipes 25 to the conduits 21 and from thence to the service or drain pipes 22. As it is found desirable to create a partial vacuum in the pipes 21 to expedite the delivery of the volatile hydrocarbon, the suction pumps are provided although they may be dispensed with if the still operates effectively without them. In order to prevent the pipes 24 and 25 from becoming corroded by the heat in compartments Y they are enclosed in sleeves 26 which effectively shield them from the flames and intense heat from the burners 18.

In operation the oil bearing rock is delivered from the cars C into the V-shaped depression in the grooves 6 which constitute bins for storing the same. From the bins the rock is passed into the tubes D, the upper valves 19 being open, until portions Y^a and X^a are filled with rock. The burners 18 are then lighted and as the compartments Y become heated the vapors or volatile hydrocarbon are drawn off through the pipes 24 and are transferred to a suitable condenser, (not shown), through the conduits 21 and service or drain pipes 22. When the hydrocarbons are separated from the rock residue in portions Y^a the lower valves 19 are opened and the rock falls to portions Z^a where it is permitted to remain until cool while any vapors given off are drawn off through pipes 25. The portion Y^a is again filled as well as the portions X^a and the operation is repeated, it being understood however that the cooled rock is first carried away by the endless belts 8. The heat emanating from the cooling rock in portion Z^a is delivered to the compartment X through the flue or passage 12, as is also the excess heat from compartment Y (the heating compartment), so that all excess heat which

would otherwise be lost is used in pre-heating the fresh rock carried in portions X^a of the tubes D. In this manner a great saving in the process of distilling hydrocarbon oils from rock, such as shale, is attained. Furthermore, the substantial continuity of the process effects a great saving in labor and time.

From the foregoing description taken in connection with the accompanying drawing, it is thought that a clear and comprehensive understanding of the construction, operation, and advantages of the invention may be had, but while I have shown and described the device as embodying a specific structure, I desire it to be understood that such variations may be made in the said structure, as do not depart from the spirit and scope of the invention as claimed.

20 I claim:

1. An apparatus for separating oil from rock comprising a housing, partitions in the housing forming a central compartment, partitions in the housing forming chambers, a roofing over the central compartment and chambers constituting a support for receiving and storing rock, tubes for receiving rock carried in the chambers and spaced from the walls thereof, valves dividing said tubes into receiving, distilling and cooling portions or chambers, means for heating the distilling portions, partitions in the chambers dividing the same into upper, intermediate and lower compartments, said housing provided with passages connecting the chambers for delivering heat from the heated and cooling portions of the tubes to the receiving portions whereby to preheat the rock, and means carried in the central compartments and extending into the tubes for drawing off the volatile oils and vapors.

2. An apparatus for separating oil from rock, comprising parallel sets of vertically disposed tubes, means dividing said tubes into receiving, distilling, and cooling sections, means for heating the distilling sections of said tubes, means for conveying heat radiated from the distilling and cooling sections to the receiving sections of said tubes, means common to the sets of said tubes for feeding rock thereto, means arranged between the sets of tubes for drawing off the volatile oils or vapors from the distilling sections of said tubes, and means for discharging the residue from the bottom of the cooling sections of said tubes.

3. An apparatus for separating oil from rock, comprising a housing formed to pro-

vide a plurality of compartments arranged in sets one parallel to the other, a tube disposed vertically of each of said compartments, means dividing each tube into receiving, distilling and cooling sections, means for heating the distilling sections of each tube, means for conveying heat radiated from the distilling and cooling sections of each tube to the receiving sections thereof, means for feeding rock to each of said tubes, means arranged between oppositely disposed tubes for drawing off the volatile oils or vapors from the distilling sections of the same, and means for discharging the residue from the bottom of the cooling sections of said tubes.

4. An apparatus for separating oil from rock, comprising a housing formed to provide a plurality of outer compartments arranged in sets one parallel to the other, and having a center compartment extending medially between each set of said first mentioned compartments, a tube disposed vertically of each of said outer compartments means dividing each tube into receiving, distilling and cooling sections, means for heating the distilling sections of each tube, means for conveying heat radiated from the distilling and cooling sections of each tube to the receiving sections thereof, means for feeding rock to each of said tubes, means within the center compartment of said housing for drawing off the volatile oils or vapors from the distilling sections of said tubes, and means for discharging the residue from the bottom of the cooling sections of said tubes.

5. An apparatus for separating oil from rock, comprising a housing formed of a plurality of compartments divided into upper, intermediate and lower sections, a tube disposed vertically within each of the compartments of said housing, means dividing each tube into receiving, distilling and cooling sections corresponding respectively to the upper, intermediate and lower sections of the compartment occupied by the same, means for conveying heat radiated from the distilling and cooling sections of each tube to the receiving sections thereof, means for feeding rock to each of said tubes, means arranged between oppositely disposed tubes for drawing off the volatile oils or vapors from the distilling sections of the same, and means for discharging the residue from the bottom of the cooling sections of said tubes.

In testimony whereof, I affix my signature hereto.

J CORBLEY POOL.
